TOOL FOR REMOVING A TUBELESS TIRE

Joseph E. Oliver, Le Grand, Calif., assignor to
Lester J. Gendron, Madera, Calif.

Filed July 8, 1963, Ser. No. 75,708

Term of patent 14 years

(Cl. D54—13)

FIG. 1

FIG. 3

FIG. 2

FIG. 1 is a front elevational view of a tool for removing a tubeless tire, showing my new design; and,

FIG. 2 is a side elevational view thereof.

FIGURE 3 is a rear elevational view of a tool for removing a tubeless tire, showing my new design.

I claim:

The ornamental design for a tool for removing a tubeless tire, as shown.
